(57) **CLAIM**

The ornamental design for a microphone, as shown and described.

DESCRIPTION

FIG. 1 is a front view of the first part of the microphone of the present invention, shown separately for purpose of illustration.

FIG. 2 is a top view of the first part of the microphone of the present invention, shown separately for purpose of illustration.

FIG. 3 is a back view of the first part of the microphone of the present invention, shown separately for purpose of illustration.

FIG. 4 is a bottom view of the first part of the microphone of the present invention, shown separately for purpose of illustration.

FIG. 5 is a left view of the first part of the microphone of the present invention, shown separately for purpose of illustration.

FIG. 6 is a right view of the first part of the microphone of the present invention, shown separately for purpose of illustration.

FIG. 7 is a prospective view of the first part of the microphone of the present invention, shown separately for purpose of illustration.

FIG. 8 is a front view of the second part of the microphone of the present invention, shown separately for purpose of illustration.

FIG. 9 is a back view of the second part of the microphone of the present invention, shown separately for purpose of illustration.

FIG. 10 is a top view of the second part of the microphone of the present invention, shown separately for purpose of illustration.

FIG. 11 is a bottom view of the second part of the microphone of the present invention, shown separately for purpose of illustration.

FIG. 12 is a left view of the second part of the microphone of the present invention, shown separately for purpose of illustration.

FIG. 13 is a right view of the second part of the microphone of the present invention, shown separately for purpose of illustration.

FIG. 14 is a prospective view of the second part of the microphone of the present invention, shown separately for purpose of illustration.

FIG. 15 is an illustrative view of the microphone of the present invention showing how the first part of the microphone and the second part of the microphone may be assembled for use; and,

(Continued)

FIG. 16 is an illustrative view of the microphone of the present invention when the first part of the microphone and the second part of the microphone have been assembled for use.
